UNITED STATES PATENT OFFICE.

ROBERT E. CARR, OF STERLING, KANSAS.

OILING AND PROTECTING CASE FOR VEHICLE SPRINGS.

Application filed July 14, 1926. Serial No. 122,430.

This invention relates to a case designed for housing an automobile spring or the like so as to protect it from dust and moisture and also to supply the spring with a lubricant.

5 A further object is to provide a device of this character which can be applied readily to a spring and has included therein a supplemental strip containing an absorbent for holding a lubricant.

10 With the foregoing and other objects in view which will appear as the description proceeds, the invention resides in the combination and arrangement of parts and in the details of construction hereinafter described 15 and claimed, it being understood that changes in the precise embodiment of the invention herein disclosed may be made within the scope of what is claimed, without departing from the spirit of the invention.

20 In the accompanying drawings, the preferred form of the invention has been shown.

In said drawings,

Figure 1 is an elevation of a casing applied 25 to a spring.

Figure 2 is a perspective view of the casing inverted and unlaced, the absorbent containing flaps being disconnected therefrom.

Figure 3 is a plan view of one of the flaps 30 spread out to show the patch therein.

Figure 4 is a perspective view of the reinforcing strips used with the casing.

Figure 5 is an enlarged section through a portion of one side of the casing.

35 Referring to the figures by characters of reference 1 designates a flexible casing of leather, fabric or other suitable material so shaped as to extend completely around a vehicle spring, this casing being provided 40 along its longitudinal edges with openings 2 for the reception of a lacing cord 3. Sewed or otherwise secured to the inner surface of the casing adjacent one of the longitudinal edges is an elongated flap 4 also provided

45 with apertures 5 for the reception of a lacing cord. Thus when the casing is drawn tightly about a vehicle spring one of the longitudinal edges thereof will extend between the flap 4 and the other longitudinal edge so that the lacing cord 3 can be threaded back and forth through the lapping portions of the casing and thus produce a tight connection therebetween which will exclude dust and moisture. Secured to the end 50 portions of the casing are strips 6 of a material similar to that of which the casing 1

is formed, these strips being adapted to be placed about the end shackles and bolts of the spring and to be laced together as shown at 7 so as thereby to completely house the 60 shackles and bolts. Arranged along the upper and lower portion of the casing upon the outer faces thereof are reinforcing strips 7 of spring metal riveted to the casing so as to hold the casing properly extended. These 65 strips may be provided, at their centers with side ears 8 for lapping the sides of the casing adjacent the center of the spring.

Housed within the casing at opposite sides of the center thereof are strips 9 the longitudinal edge portions of which are detachably connected by lacing cords 10. Each of these strips 9 has a series of absorbent pads 11 fastened therein, these pads being formed of felt or other suitable material. 75

In applying the structure constituting the present invention the pads 11 are supplied with a lubricant until saturated therewith. The strips 9 are then fastened around the springs at opposite sides of the center thereof after which the casing 1 is slipped onto the spring from one side so as to enclose the strips 9. One longitudinal edge of the casing is then inserted between the flap 4 and the other longitudinal edge and the parts 85 held together by a lacing cord as shown in Figure 1. The end strips 6 are also laced about the shackles and bolts at the ends of the spring so that the spring is thus completely concealed and fully protected from 90 moisture and dust. At the same time lubricant is constantly supplied to the spring from the pads 11. By providing the tongues or ears 8 on the spring strips 7, the casing is held against lateral displacement relative 95 to the strips. Strips 7, as before pointed out, hold the casing properly extended along the vehicle spring so that said casing will not crumple.

If desired outlets 12 can be formed in the 100 casing to allow any moisture that might get into the casing to drain therefrom readily.

What is claimed is:

1. A device of the class described including a casing for the reception of a vehicle 105 spring, said casing having interfitting longitudinal edge portions, a lacing cord for holding said interfitting portions together detachably, and reinforcing spring strips secured upon opposed portions of the casing. 110

2. A device of the class described including a flexible casing for the reception of a

vehicle spring, said casing having interfitting longitudinal edges, means extending through the interfitting edges of the casing for holding them together detachably, reinforcing spring strips secured upon opposed portions of the casing and extending longitudinally thereof, and ears extending from said spring strip for lapping the sides of the casing.

10 3. A device of the class described including a flexible casing for the reception of a vehicle spring, said casing having interfitting longitudinal edges, means extending through the interfitting edges of the casing for holding them together detachably, means at the ends of the casing for housing the shackles and bolts of the spring, spring strips secured to and extending longitudi-

nally of the top and bottom of the casing respectively, said strips constituting reinforcements for the casing, and ears extending from the spring strips and lapping the sides of the casing, the ears on each strip also lapping the ears on the opposed strips.

20 4. A device of the class described including a casing for the reception of a vehicle spring, said casing having interfitting longitudinal edge portions, a lacing cord for holding said interfitting portions together detachably, and reinforcing spring strips secured upon opposed portions of the casing, there being drain openings in the bottom portion of the casing.

25 In testimony that I claim the foregoing as my own, I have hereto affixed my signature.

30 ROBERT E. CARR.
